COAL SEPARATOR

Frank C. Wright, Jr., Tarrytown, N. Y., assignor
to Penn Anthracite Collieries Company, Scranton,
Pa., a corporation of Pennsylvania

Application May 27, 1935, Serial No. 23,743

4 Claims. (Cl. 209—159)

This invention relates to improvements in apparatus for the separation of materials of different specific gravities by the floatation process, and more particularly for the separation of coal and slate. In the type of apparatus to which my invention is applicable, the coal, containing slate as its principal impurity, is fed into a conical receptacle which is kept filled with a fluid mass having a specific gravity higher than that of coal and lower than that of slate, so that the coal floats while the slate sinks in the mass. A shaft arranged vertically in the cone carries agitator arms below the floating coal and these cause a circular motion of the liquid mass and hence a flow of the floating coal from the feeding point to a weir at the opposite side of the cone where the coal passes out of the cone. In separators of this type in commercial use, some of the slate which should sink to the bottom of the cone floats out with the coal, and the purpose of the present invention is to remedy this defective separation.

In the accompanying drawing.

Fig. 1 is a vertical section through the separator on the line 1—1 of Fig. 2, and,

Fig. 2 is a plan view of the same, the agitator shaft being in section on the line 2—2 of Fig. 1.

The type of separator to which my invention relates is illustrated in U. S patents to T. M. Chance Nos. 1,556,676, 1,605,172, and 1,937,190, and in the accompanying drawing sufficient of the separator is shown to illustrate my improvements. The conical receptacle in which the separation of the coal and slate takes place is indicated at *a*, the discharge chute for the slate is indicated at *b*, and *c* indicates the chamber into which the slate is discharged at intervals and trapped out of the separator through the medium of valves *d* and *e*. The power operated shaft *f* extends downwardly into the cone, axially thereof, and carries agitator arms *g* and *h*.

In the method of separation carried out in separators of this type, the cone is kept filled with water and finely comminuted insoluble material, such as sand, and the liquid mass is agitated by the agitating arms and also by the injection of water through suitably placed nozzles *i*, the agitation keeping the sand afloat and distributed in the liquid. The specific gravity of the liquid mass, composed of the water and sand, is greater than that of the coal and less than that of the slate, so that the coal will float in the upper part of the cone while the slate will sink to the bottom. The agitator arms cause a circular movement of the liquid. The coal prepared

as to size but containing impurities which come with it from the mines, is delivered into the liquid at one side of the cone through a suitable chute *2*, and the coal, which floats near the surface, is carried around to a weir *3* at the opposite side of the cone and passes out of the cone over a suitable screen *4* through which any liquid and sand passing out with the coal are drained off. The slate sinks through the liquid to the outlet end of the cone and is trapped out. The sand and liquid carried out with the coal and slate are pumped back into the cone through a pipe *5*.

In commercial machines of this type, the larger pieces of slate and most of the smaller pieces sink, but some of the smaller pieces of slate pass out with the coal. The floating coal is submerged and the liquid is dark and it is impossible to determine by sight whether any slate is mingled with the floating coal. I have found, however, especially with the smaller sizes of coal, that pieces of coal gathered in closely compacted masses or clusters float in the liquid, like floating islands and small pieces of slate, usually flat, which become enmeshed with these clusters, pass out through the weir with the coal.

In order to break up these clusters and permit the entrained pieces of slate to sink, I provide a series of vertically arranged barriers in the form of rods *6* which are extended down through the zone in which the coal floats to a short distance above the uppermost agitator arms *g*, which arms, as shown in the drawing, may have an upwardly extending series of spaced pins *7*. Where such pins are used, I find it desirable to make them long enough to extend into the zone of the floating coal. The barrier rods *6* are secured to a plate *8* which is supported at the top of the cone on parallel beams *9* and *10* which extend diametrically across the top of the cone at opposite sides of the shaft. The plate *8* extends diametrically across the cone on a line over the coal stream passing from the inlet *2* to the weir *3*. The barrier pins are spaced apart the proper distance to permit the pins *7* on the agitator arms to pass between them as the agitator rotates. Any clusters of coal carried around by the liquid will be broken up by contact with the barriers, and any slate carried by the clusters will be released and will drop downward in the liquid. It is found that the addition of the barriers described, by causing the disintegration of the floating clusters and the consequent release of slate carried by these clusters, results in a much cleaner product than can be obtained without the barriers.

What I claim is:

1. A separator of the class described comprising a conical receptacle, a fluid mass therein comprising a liquid and finely comminuted material heavier than the liquid, agitating means comprising a rotatable shaft axially arranged in the cone and having an arm thereon provided with upwardly extending radially spaced rods for agitating and giving a circular motion to the liquid; an inlet for unprepared coal at one side of the cone and a weir for the outlet of coal at the opposite side of the cone; and a series of radially spaced baffle rods supported above the liquid and extending into the liquid in the zone traversed by the floating coal, the baffle rods and the rods on the agitator arm being so spaced that the latter will pass between the former as the arm rotates.
2. A separator of the class described comprising a conical receptacle, a fluid mass therein comprising a liquid and finely comminuted material heavier than the liquid, agitating means comprising a rotatable shaft axially arranged in the cone and having an arm thereon provided with upwardly extending radially spaced rods for agitating and giving a circular motion to the liquid, said rods extending through the zone traversed by the floating coal, an inlet for unprepared coal at one side of the cone and a weir for the outlet of coal at the opposite side of the cone, and a series of radially spaced baffle rods supported above the liquid and extending into the liquid through the zone traversed by the floating coal, the baffle rods and the rods on the agitator arm being so spaced that the latter will pass between the former as the arm rotates.
3. A separator of the class described comprising a conical receptacle having an outlet for slate at

its lower end, a fluid mass in said receptacle comprising a liquid and comminuted material heavier than the liquid, said receptacle being free from obstruction to the passage of slate or coal downward by gravity from the top of the liquid to said outlet; an inlet for unprepared coal at one side of the cone and a weir for the outlet of coal spaced peripherally from said inlet, agitating means for maintaining said finely comminuted material in suspension and, causing the coal to float in the upper part of the receptacle comprising a rotatable shaft axially arranged in the cone and having means thereon for agitating and giving circular motion to the liquid, and baffle rods supported above the liquid and extending into the liquid in the zone traversed by the floating coal.

4. A separator of the class described comprising a conical receptacle having an outlet for slate at its lower end, a fluid mass in said receptacle comprising a liquid and comminuted material heavier than the liquid, said receptacle being free from obstruction to the passage of slate or coal downward by gravity from the top of the liquid to said outlet, an inlet for unprepared coal at one side of the cone and a weir for the outlet of coal spaced peripherally from said inlet, agitating means for maintaining said finely comminuted material in suspension and, causing the coal to float in the upper part of the receptacle comprising a rotatable shaft axially arranged in the cone and having means thereon for agitating and giving circular motion to the liquid, and a series of radially spaced baffle rods supported above the liquid and extending into the liquid in the zone traversed by the floating coal.
